ALBERT A. SINGLER

331 A. J. Boosk Attorney

UNITED STATES PATENT OFFICE.

ALBERT A. SINGLER, OF DENVER, COLORADO.

PHONOGRAPH CABINET.

1,414,379.

Specification of Letters Patent. Patented May 2, 1922.

Application filed August 18, 1921. Serial No. 493,841.

To all whom it may concern:

Be it known that I, ALBERT A. SINGLER, a citizen of the United States, residing at the city and County of Denver and State of Colorado, have invented certain new and useful Improvements in Phonograph Cabinets; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 The object of my invention is to provide a cabinet for use in connection with phonographs and the like in which the cabinet is so designed that it can be used as a table for supporting books, record albums or a lamp, 20 or any article without the necessity of removing said articles when operating the phonograph.

My improved cabinet can be placed in a corner or along a wall or used in the center 25 of the room without in any way interfering with the operation of the phonograph.

My improved cabinet also permits the top 30 to be folded back upon itself or slid to the side or tilted in the manner usually employed in cabinets of this type.

It is a further object of my invention to improve the acoustic properties of the phonograph by changing the shape and location of the amplifying horn, and to provide 35 the same with means for improving the quality of the sound in a manner to be pointed out hereafter.

My cabinet is so designed that the four sides are symmetrical and it can therefore be 40 used in the middle of a room, if desired, since it has no unfinished side that must be concealed by backing the same against a wall.

In order to more clearly describe my improved cabinet I shall refer to the accompanying drawings in which:

Fig. 1 is a front elevation of my improved cabinet.

Fig. 2 is a vertical section taken on line 50 2—2, Fig. 1.

Fig. 3 is a view showing the top slid to one side.

Fig. 4 shows the top in tilted position.

Fig. 5 is a top view of the cabinet with 55 the parts in the position shown in Fig. 3.

Fig. 6 is a section on line 6—6, Fig. 2.

Fig. 7 is a section on line 7—7, Fig. 5.

Fig. 8 is a section on line 8—8, Fig. 5.

Fig. 9 is a detail view of the supporting member, and

60

Fig. 10 is a section on line 10—10, Fig. 9.

The same reference characters indicate the same parts in the several views.

My improved cabinet, which I have indicated as a whole, by reference numeral 1, 65 comprises a substantially rectangular cabinet having sides 2 and 3, a back 4 and a front 5, said front member 5 being hinged at one side and serving as a door. The cabinet is supported on ornate legs 6 and an ornamental column 7 extends along each corner from the bottom 8 to the top 9. Beneath the bottom 8 and joining the four legs 6 is an apron 10 which may have its lower edge formed into ornamental curves if desired. Within 70 the cabinet I provide a container 11 which forms a receptacle for the reception of records or record albums 12 (Fig. 6). Container 11 terminates short of the rear wall 4, so as to provide a space for the amplifying 75 horn 13. The top 9 of my cabinet forms a support for the sound reproducing machinery which comprises a motor 14, a turntable 15 and the arm 16 which carries the reproducer 17. The sound reproducing 80 mechanism is enclosed by a box-like structure comprising front and back pieces 18 and 19 and sides 20 and 21. Secured to members 18, 19, 20 and 21 by suitable means 85 is a top 22 comprising two parts 23 and 24 which are hinged together by means of 90 hinges 25. The top 22 is secured to the cabinet in the following manner. Front and 95 back members 18 and 19 are provided near their top edges with a cut away portion comprising a groove 26 for the reception of a molding 27. Said molding has a projecting portion 28 which fits with a sliding fit into groove 26. Molding 27 also has a cut away portion 29 for the reception of a strip 30 which is glued or nailed to sides 18 and 19. 100 It will thus be seen that moldings 27 can slide in grooves 26 but that they cannot be removed on account of the strip 30. One end of moldings 27 is connected by means of a third strip of molding 31 which fits in a cut 105 away portion 32 of side 21. The upper edge of side 20 is shaped to correspond with the shape of the molding around the other three sides. It will be seen from the above that I 110 have provided a frame of three sides consisting of moldings 27 and 31 which can

be slid cross ways of the cabinet top. The top 22 is hinged to side molding 27 by means of hinges 33 and provided with holes 34 for the reception of dowel pins 35 which 5 project upwardly from the top of the co-operating molding 27 on the front of the cabinet. The top 22 can therefore be slid crosswise of the cabinet to the position shown in Fig. 3 or it may be raised to the 10 position shown in Fig. 4. In order to hold the cover in the raised position I provide a support 36 which is releasably pivoted to the cover at 37 in a manner which will be described more in detail hereafter. Hinges 33 15 are so placed with respect to molding 27 that the pivot pins are accessible and the hinge nearest to the side 20 is so constructed that the pivot pin can be readily removed. When it is desired to fold the top back upon itself 20 so that member 23 will occupy a position directly over member 24, the pivot pin is first removed from the hinge attached to member 23.

When the top is doubled as shown dotted 25 in Fig. 1, the box containing the reproducing apparatus is sufficiently accessible to permit the records to be changed, but if it should be desirable to have the entire top open, this may be accomplished by sliding the top 30 to the side in the manner indicated in Figs. 3 and 5, or the top member may be raised or pivoted about hinges 33, member 24 being preferably provided with a pair of hinges so as to permit this tilting with perfect safety.

Instead of having the amplifying horn 13 40 open above the record container 11, as is customary, I extend it down behind the record container and bend it forwardly just underneath the bottom of the cabinet as indicated at 38. By placing the amplifying horn in the position indicated, I can make my cabinet symmetrical and have all of the 45 four sides substantially identical in appearance.

On top of members 18, 19, 20 and 21, and below top 22 I have provided a slide 39 which is of a width substantially equal to one-half of the width of the cabinet and can 50 be freely moved backward or forward and can be used to close the top of the cabinet when the machine is operated with the top slid back as indicated in Figs. 3 and 5 or when member 23 is folded back upon member 24 as indicated in Fig. 1. Slide 39 has a cutout portion 40 for the reception of support 36.

For supporting the top 22 in inclined position as shown in Fig. 4, I have designed 60 a supporting member 36 one end of which is provided with a spring member 41 and the other end with a hook (not shown) for engaging with the transverse portion 42 of plate 43 (Fig. 5). Secured to member 24 65 of top 22 is a plate 44 having a hole 45 and

a portion 46 which projects part way across said hole 45 (Fig. 10). Pin 46 engages in a hole near the end of support 36. Spring 41 serving to hold the supporting member on said pin. When the top is slid to the left 70 as indicated by dotted lines in Fig. 9, support 36 will engage with the inside of side 21 and pin 46 will be pulled out of its co-operating hole in member 36 permitting the support to drop down to the position shown 75 in dotted lines in Fig. 9.

In order to enrich the tones of the machine I provide the ends of the amplifying horn 13 with a number of strings 47 (Fig. 2) : these strings are tensioned to any desired 80 degree and will vibrate in sympathy with the corresponding tones from the instrument. I have indicated only three strings in the drawings but I may have any number desired as, for example, eight, which may be 85 tuned to form an octave or in any other way found to be the most desirable and effective.

From the above description it is apparent that I have invented a cabinet especially 90 adapted to contain and house a sound reproducing machine and its essential parts and which is so constructed that its top surface may be used as a table for the support of any desirable article which need not 95 be removed whenever the machine is to be operated. The cabinet is so built that the four sides are substantially the same in appearance and the amplifying horn is so located that it becomes unnecessary to provide 100 a special opening for the emission of the sound.

The top of container 11 may be used for supporting various things, as, for example, a box 48.

I am aware that various minor changes may be made in the construction of my cabinet without departing from the real invention and I desire that the specific cabinet which I have shown and described shall be 110 taken in an illustrative and not a limiting sense.

Having thus described my invention or discovery and the preferred way of making and using the same, what I claim is:

1. In a cabinet of the type used for the housing of sound reproducing machines, a box for the reception of the turntable and sound reproducing arm, a top for said box comprising two members hingedly connected 120 to one another, a frame slidably connected to the top of said box and means for movably securing said top to said frame whereby said frame and said top may be simultaneously moved with respect to said box and the top 125 moved relative to the frame.

2. In a cabinet of the type used for the housing of sound reproducing machines, a box for the reception of the turntable and sound reproducing arm, a top for said box,

grooves along the top edges of two sides of said box, moldings provided with means having sliding engagement with said grooves, means for retaining said moldings in said 5 grooves, a third molding joining corresponding ends of the first mentioned moldings, a top hingedly connected to one of said slidable moldings, dowel pins and holes for connecting the top with the other slidable 10 molding, said top being made in two parts hingedly connected to one another.

3. In a cabinet of the type used for the housing of sound reproducing machines, a box for the reception of the turntable and 15 sound reproducing arm, a top for said box, grooves along the top edges of two sides of said box, moldings provided with means having sliding engagement with said grooves, means for retaining said moldings in said 20 grooves, a third molding joining corresponding ends of the first mentioned moldings, a top hingedly connected to one of said slidable moldings, dowel pins and holes for connecting the top with the other slidable molding, said top being made in two parts hingedly 25 connected to one another.

edly connected to one another, and a slide between said top and the top edges of said box.

4. In a cabinet of the type used for the housing of sound reproducing machines, comprising a box for the reception of the turntable and the sound reproducing arm, a top for said box, means permitting said top to be tilted with respect to said box and means for holding said top in tilted position 30 comprising in combination a supporting bar (36) having a hook near one end thereof and a hole near the other end thereof, a plate (43) in the bottom of said box for cooperating with said bar, a transverse piece (42) on said plate for cooperating with said hook, a plate (44) secured to said top, means (46) on said plate for engaging with the hole in said bar and a spring (41) for cooperating with the plate (44) on the top for holding said bar (36) in contact with said pin (46).

In testimony whereof I affix my signature.

ALBERT A. SINGLER.
